UNITED STATES PATENT OFFICE.

REUBEN B. EUBANK, JR., OF KANSAS CITY, MISSOURI, ASSIGNOR TO THE BICYCLE SKATE & MFG. CO., A CORPORATION OF MISSOURI.

ROLLER-SKATE.

No. 920,848.

Specification of Letters Patent.

Patented May 4, 1909.

Application filed June 9, 1908. Serial No. 437,480.

To all whom it may concern:

Be it known that I, REUBEN B. EUBANK, Jr., a citizen of the United States, residing at Kansas City, in the county of Jackson and 5 State of Missouri, have invented certain new and useful Improvements in Roller-Skates, of which the following is a specification.

My invention relates to improvements in roller skates; and it consists in the novel construction, combination, and arrangement of parts hereinafter described, pointed out in the claims, and illustrated in the accompanying drawings.

Referring now to said drawings, Figure 1 15 represents a side elevation of my improved skate. Fig. 2 is an inverted plan view of the same. Fig. 3 is an inverted plan view of the foot-plate of the skate with a number of parts removed. Fig. 4 is a transverse section on line IV—IV of Fig. 2. Fig. 5 is a broken inverted plan view of the foot-plate. Fig. 6 20 is a section on line VI—VI of Fig. 2. Fig. 7 is an irregular vertical section on line VII—VII of Fig. 1.

25 In carrying out the invention I employ a foot-plate 1 having two pairs of depending lugs 2 and 3, a pair of upwardly-extending lugs 4, and a pair of upwardly-extending loops 5.

30 6 designates a rear bracket pivotally secured at its forward end by a pin 7 to lugs 2, so that its rear portion may have limited up and down movement.

35 8 designates a cushioning-device in the form of a pair of coil springs interposed between the foot-plate and bracket 6 and embracing a pair of studs 9, fixed to the foot-plate and extending loosely through the rear portion of the bracket. The lower ends 40 of studs 9 are provided with retaining-nuts 10, which limit the downward movement of the rear portion of bracket 6.

45 11 designates a member pivotally secured by a bolt 12 to the front end of the foot-plate so that its rear end may swing laterally to said foot-plate, and in order that said swinging movement will be attended with but little friction I interpose a ball-bearing 13 between the front end of the

50 pivoted member and the foot-plate, and a ball-bearing 14 between the rear end of said member and the foot-plate. Member 11 is provided near its forward end with a pair of depending lugs 15 and its rear end is 55 prevented from springing downward by a

segmental retaining-plate 16 secured to the underside of the foot-plate.

17 designates a pair of rearwardly-diverging springs secured at their forward ends to the rear terminal of member 11 for 60 the purpose of normally holding the same in alinement with the longitudinal axis of the foot-plate. The rear ends of springs 17 are secured to tensioning devices 18 extending through lugs 3. 65

19 designates a front bracket pivotally secured to lugs 15 by a pin 20, so that its rear end may swing up and down. Said swinging movement is limited by a pair of retaining-nuts 21 secured to a pair of studs 70 22 fixed to the rear end of member 11 and extending loosely through bracket 19. A cushioning-device in the form of a pair of springs 23 is interposed between the rear portion of member 11 and bracket 19. By 75 securing bracket 19 to the pivoted member 11 convenient means is afforded whereby the skater may describe curves without lifting the skates from the floor.

24 designates a pair of axles secured to the 80 lower ends of brackets 6 and 19, and provided with a pair of rollers 25, which are preferably of metal as I have found by practice that the cushioning-devices 8 and 23 answer the same purpose as rubber-tires in 85 absorbing shocks caused by the rollers passing over obstructions, and are much more durable than said tires.

26 designates a pair of braces for relieving the ankles of the skater of lateral strain. Said 90 braces are pivotally secured to lugs 4 by bolts 27 and are provided with downwardly and forwardly-extending arms 26^a, provided at their lower ends with a pair of ratchet-heads 28, upon which the upper end of a yoke 29 is 95 adjustably secured by means of a bolt 30 and a clamping-nut 31, so that a rotary brake-shoe 32 journaled in the lower portion of the yoke may be adjusted toward or away from the rear roller 25. The brake-shoe 32 forms 100 a convenient means for controlling the speed or stopping the skate, as it may be thrown into contact with the rear roller 25 by inclining the braces 26 forwardly.

33 designates a flexible metallic strap connecting the lower portions of the braces, and 105 34 designates a leather band secured to the upper ends of said braces and provided with buckles 35 whereby it may be firmly secured in position on the skater's limb. 110

36 designates a toe-strap provided with a buckle 37.

38 designates an instep-strap provided with a buckle 39 and secured to a pair of loops 40 pivotally mounted on bolts 27.

41 designates a clamp for assisting straps 36 and 37 in securing the skate to the skater's shoe. One side of said clamp is pivotally secured to the underside of the foot-plate by a 10 bolt 42 and a nut 43, while the other side of said clamp is secured to a cam 44 whereby it may be adjusted into or out of engagement with the sole of the shoe. The two sides of the clamp are further secured in position by 15 loops 45 at the underside of the foot-plate 1.

Having thus described my invention, what I claim is:-

1. A roller skate consisting of a foot-plate, front and rear brackets beneath the same, 20 rollers mounted in said brackets, a member pivoted at its forward end to the front end of the foot-plate so that its rear end may swing laterally, means pivotally connecting the forward end of the front bracket to said pivoted 25 member so that its rear end may swing up and down, and a cushioning device interposed between the rear end of the pivoted member and said front bracket.

2. A roller-skate consisting of a foot-plate, 30 front and rear brackets beneath the same, rollers mounted in said brackets, a member pivoted at its forward end to the front end of the foot-plate so that its rear end may swing laterally, means pivotally connecting the forward end of the front bracket to said pivoted 35 member so that its rear end may swing up and down, studs extending down from the rear end of the pivoted member through the rear end of the front bracket and vertically- 40 slidably therein, and springs interposed between said bracket and the rear end of the pivoted member.

3. A roller-skate consisting of a foot-plate, means for securing the same to a skater's foot, front and rear brackets beneath the same, 45 rollers mounted in said brackets, a member pivoted at its forward end to the front end of the foot-plate so that its rear end may swing laterally, means pivotally connecting the forward end of the front bracket to said pivoted member so that its rear end may swing up and down, and a cushioning device interposed between the rear end of the pivoted member and said front bracket.

4. A roller skate consisting of a foot-plate, 50 front and rear brackets beneath the same, rollers mounted in said brackets, a member pivoted at its forward end to the front end of the foot-plate so that its rear end may swing laterally, resilient means secured to the rear 55 end of said pivoted member for normally holding the same in line with the longitudinal axis of the foot-plate, means pivotally connecting the forward end of the front bracket to said pivoted member so that its rear end 60 may swing up and down, and a cushioning device interposed between the rear end of the pivoted member and the front bracket.

5. The combination with a roller skate, of a brake consisting of a pair of braces pivotally secured to the rear portion of the skate and provided with downwardly and forwardly-inclined arms, a yoke adjustably secured to the lower terminals of said arms and terminating near the rear roller of the skate, 75 and a rotary brake-shoe mounted in said yoke and adapted to engage said rear roller.

In testimony whereof I affix my signature, in the presence of two witnesses.

REUBEN B. EUBANK, JR.
